MARKER LIGHT FOR RUNWAY PAVEMENTS OR THE LIKE

James F. Angier, Takoma Park, Md., assignor to Structural Concrete Products Corp., New York, N.Y., a corporation of Delaware

Filed Dec. 31, 1959, Ser. No. 58,865

Term of patent 14 years

(Cl. D72—3)

FIG. 2

FIG. 3

FIG. 4

Fig. 1 is a perspective view of a marker light for runway pavements or the like showing my new design;

Fig. 2 is a top plan view thereof shown on a reduced scale.

Fig. 3 is a side elevational view thereof as shown in Fig. 2.

Fig. 4 is an end elevation view thereof as shown in Fig. 2.

I claim:

The ornamental design for a marker light for runway pavements or the like, as shown.
